UNITED STATES PATENT OFFICE.

FELIX M. BAUDOUIN, ACHILLE BAUDOUIN, AND JEAN B. F. JOUANNIN,
OF PARIS, FRANCE.

IMPROVEMENT IN LOOMS FOR MAKING FISHING AND OTHER NETS.

Specification forming part of Letters Patent No. 43,888, dated August 16, 1864.

To all whom it may concern:

Be it known that we, FELIX M. BAUDOUIN, ACHILLE BAUDOUIN, and JEAN B. F. JOUANNIN, of Paris, in the Empire of France, have invented a new and Improved Loom for Making Nets; and we do hereby declare that the following is a full, clear, and exact description thereof, which will enable others skilled in the art to make and use the same, reference being had to the accompanying drawings, forming part of this specification, in which—

Figure 1 represents a longitudinal vertical section of our invention. Fig. 2 is a front elevation of the same. Fig. 3 is a plan or top view of the same. Fig. 4 is a longitudinal vertical section of the hook-box. Fig. 5 is a detached side elevation of our device for regulating the "take-up" motion and the length of the meshes. Figs. 6, 7, and 8 are detached sectional views of one of the shuttles. Figs. 9 and 10 are detached views of the shuttle-thread stretchers.

Similar letters of reference indicate like parts.

This invention relates to certain improvements in the mechanism for forming the loops and tying the knots; also, in the construction of the shuttles and the means employed for operating and moving the same; further, in the use of an automatic take-up regulator, which also serves to regulate the length of the meshes; also, in a peculiar arrangement and disposition of the warp-threads, whereby the length of the net becomes unlimited, and each thread can be readily tied in case it breaks; finally, to certain novel means for keeping the threads stretched and to take up the slack.

A is a frame made of cast-iron or any other suitable material of sufficient strength and durability for the purpose. This frame forms the bearings for the several arbors and working parts of our loom.

Secured to the rear end of the frame A is the secondary frame B, which forms the bearings for the arbors of the spools a, which carry the warp-threads. These spools may be arranged in a horizontal or in any other convenient position, and their number is equal to the number of threads to be used in the warp of the net to be produced. Said warp-threads pass from the spools a over a stationary

comb, b, which is secured in the top part of the main frame A, and thence they extend under the rod c and the rod c', and then down under the rod d, which is fastened to two arms, d', oscillating freely up and down on pivots or trunnions set in suitable sockets in the main frame. This rod serves to take up the slack of the warp-threads, and the proper tension of said threads is effected by passing them from the comb b under and over the rods c c'. From the rod d said threads extend around the roller e, the surface of which is covered with emery or otherwise, made rough to prevent the threads from slipping in either direction and from passing one on top of the other. Each thread passes round the roller e one and a quarter time, and, notwithstanding the small amount of friction-surface thus produced, the rough surface of the roller is sufficient to prevent said threads from slipping either on the roller or in a lateral direction. The threads are thus kept distinct and separate, one from the other, and if one of the threads breaks it can be readily tied by a single knot without producing any change in the tension of the other threads.

The axle e' of the roller e has its bearings in the main frame A, and it bears on one end a pulley, e², to receive a cord, e³, the ends of which pass over sheaves e⁴ e⁵, pivoted to an arm, e⁶, which extends from the frame A, and suspended from the ends of this cord are two unequal weights, e⁷ e⁸, which are so balanced that the heaviest of the two weights always has a tendency to rotate the roller e in the direction of the arrow marked thereon in Fig. 1. These weights are intended to reverse the motion of the roller e after finishing each course of meshes; but they have not always sufficient power to accomplish this task when some obstruction occurs in the loops. For this reason we have arranged a friction-driver, e*, to operate in connection with the balance weights e⁷ e⁸. This friction-driver is secured to the main driving-axle C of the loom, and its beveled face acts on the beveled face of the roller e**, which is secured to the arbor of the roller e. The faces of the driver e* and roller e** are beveled in opposite directions, so that they can be set up closer and closer to compensate for wear.

From the roller e the warp-threads pass

down through the movable comb f , being confined in its teeth by a bar, f' , which extends across the comb in contact with the points of its teeth. Said comb is guided by dovetailed brackets f^2 on the front end of the main frame A, and a reciprocating motion is imparted to it by a cam, f^3 , which acts on a friction-roller, f^4 , secured to the end of an arm which extends from one end of the comb-stock, and held up against the face of the cam by a spring, f^5 , acting on the opposite end of the comb stock.

The cam f^3 has its bearings on a pivot that is firmly inserted in the side of the main frame, and it is secured to or cast solid with a cog-wheel, f^6 , which gears in a pinion, f^7 , mounted on the main driving-shaft C. The diameter of the wheel f^6 is twice as large as that of the pinion f^7 , so that it takes two revolutions of the driving shaft C to produce one of the cam f^3 . The face of the cam, however, is provided with two steps, and each revolution of the main shaft brings one of the steps in contact with the roller f^4 , and an intermittent reciprocating motion is thereby imparted to the comb f . By this motion the warp-threads are displaced after completing each course of meshes, and the hooks g are compelled to catch hold of them on the other side. The threads are thereby twisted in opposite directions, and the tendency of the net to twist during the fabrication and when the same is in use is destroyed.

The hooks g are secured in the hook-box g' , and they receive a complex motion which enables them to take up the weft or shuttle threads and the warp-threads, twist them, draw them out to form loops, and deposit these loops on the shuttles.

The hook-box g' is supported by a rod, g^2 , the round ends of which project beyond said box and have their bearings in rods g^3 , the rear ends of which are made to straddle the shaft, C', and this shaft carries two disks, C'* $, with cam-grooves g^4 , acting on roller-studs which are secured to the rods g^3 . Said rods are suspended from straps g^6 , which embrace the ends of the driving-shaft C, and the upper ends of which carry roller-studs g^7 , to catch into cam-grooves g^8 , cut into disks that are mounted on the shaft C. By the action of the cam-grooves g^8 the hook-box is raised and lowered at stated intervals, and at the same time said box is moved backward and forward by the action of the cam-grooves g^4 on the rods g^3 . Besides these two motions, a revolving motion is imparted to the hook-box by the action of a toothed rack-bar, g^9 , the forked rear end of which straddles the shaft C', and which carries a roller-stud, g^{10} , to engage with a cam-groove, g^{11} , on the inner surface of one of the disks C'* $. By the action of this cam-groove a reciprocating motion is imparted to the rack-bar g^9 at the proper intervals, and the hook-box is turned up or down, as may be required. The hook-box also receives a lateral reciprocating motion by the action of projections and corresponding cavities on the inner sur-$$

faces of lugs g^{12} , secured to the sides of the frame A. These surfaces bear on the ends of a bar, g^{13} , which is firmly fastened in the ends of the rods g^3 , and as said rod rises and falls with the hook-box it is alternately pushed toward one side or toward the other as it comes in contact with the projections on either of the lugs g^{12} . This lateral motion of the hook-box is requisite to enable the hooks to take hold of the warp threads and to carry them forward in the form of loops, to be deposited on or passed over the shuttles.

The hooks g rotate freely in the hook-box, and their shanks are provided with pinions g^* , which gear into teeth cut or otherwise formed in the rod g^2 , which supports the hook-box. This rod is provided with a double flange forming a groove, g^{**} , at one end, to receive the forked end of the lever g^{**} , which has its fulcrum on a pin inserted into a standard, g^{***} , rising from one of the rods g^3 . The rear end of this lever bears against the face of a cam, g^{4*} , on the shaft C', and by this cam a lateral reciprocating motion is imparted to the rod g^2 independent of the hook-box. In receiving this motion the teeth of this rod engage with the pinions on the shanks of the hooks, and said hooks revolve in the desired direction and at the proper time to seize hold of and twist the threads used in weaving the nets.

The weft or shuttle threads are wound on bobbins h , which are placed loosely within the shuttles h' . Said bobbins are held in place by central ribs catching in a groove on their circumference, and by turning up the flaps h^* they can be easily removed for the purpose of receiving a fresh supply of thread.

The shuttles are attached to a shaft, h^2 , by means of flanged circular shoes h^3 , which slip into L-shaped slots in the bottom of the shuttles, as clearly shown in Fig. 8 of the drawings, a portion of the flange on each being taken off in order to enable the same to pass into its slot. A recess or notch, h^4 , made in the circumference of each shoe, (see Fig. 6,) serves to receive the loops carried down by the hooks g and deposited by them on the shuttles, and by imparting to the shaft carrying the shoes a partial revolution the loops are passed through under the shuttles and deposited on the needles h^5 , as shown in Fig. 6.

The shaft h^2 has its bearings in suitable boxes in a carriage, h^7 , which rests on the rails h^8 , and to which a reciprocating motion is imparted by connecting rods h^9 , extending from eccentric wrist-pins in the faces of disks or cranks secured to the ends of the shaft C'. As the carriage is drawn backward and forward on the rails h^8 , a forked arm, h^{10} , secured to one end of the shaft h^2 , by coming in contact with a stud, h^{11} , projecting from the frame A, imparts to said shaft a partial rotary motion, thereby bringing the recesses h^4 alternately in the position to receive and deliver the loops formed by the action of the hooks g . The shuttle-threads extend from the bobbins

h round hooks h^2 , extending from each shuttle, as clearly shown in Fig. 6 of the drawings, and thence over the oscillating stretcher *i* to the jaws *k*, and finally through these jaws to the take-up rollers. This stretcher serves to produce the requisite tension of the shuttle-threads, and to take up the slack after the loops have been formed. It oscillates on a rod, i' , which revolves on center points fastened in the lower part of the frame A, and motion is imparted to it by an eccentric, i^2 , on the shaft C', which connects with one of the arms of said stretcher by a rod, i^3 . The stretcher itself is hinged to the upper ends of said arms, and it swings backward and forward, its motion being limited by studs projecting in suitable sockets in the edges of the arms. By this motion of the stretcher the strain is rendered yielding, and the machine can be worked quickly without danger of snapping the threads. (See Figs. 9 and 10.)

The needles h^5 are hinged to the inner ends of the shuttles h' , and they are intended to receive the loops as the same pass off from the bodies of the shuttles, and to prevent the twisting of said loops, and also the untimely formation of the knots. By their action the regularity of the work is insured.

Before starting the machine the ends of the warp-threads are drawn from the comb *f* through the jaws *k*, and wound round the take up rollers, so that the same are firmly retained in position, and the hooks *g*, in pulling on said threads, will be able to carry in a new supply sufficient for a loop by every stroke. At the moment when the shuttle carriage is at its greatest distance from the jaws *k*, the hook-box *g'* receives a downward motion, in order to make the hooks proceed toward the weft or shuttle threads; and while their downward motion is being accomplished the hooks turn on their own axis, so as to direct their points downward and cause them to pass between the shuttle-threads. At that point a lateral motion is imparted to the hook-box by the projections on the lugs g^{12} acting on the ends of the bar g^{13} , and by this motion the hooks are brought beneath the shuttle-threads made to catch hold of them, and then the hook-box rises and again moves laterally to enable the hooks to catch hold of the warp-threads, and the hooks are turned a quarter of a revolution to direct their points downward and depressed, thus causing the loops of the shuttle-threads to slip from the hooks upon the warp-threads, said warp-threads still being retained by the hooks and drawn through the loops of the shuttle-threads; and as the hooks descend the loops of the warp-threads are deposited upon the shuttles, and, after passing over said shuttles, upon the shuttle-thread, as indicated in Fig. 6 of the drawings.

Each course of loops, after having been formed as above described, is drawn through the jaws *k* by the action of the take-up rollers l l' l^2 , which are arranged side by side on axles l^* l^{*2} l^{*3} , having their bearings in slots in the

opposite sides of the frame A. The surfaces of these rollers are made rough by means of emery, or in any other suitable manner, to enable them to take a firm hold of the net, and their surfaces are compressed with more or less power by set-screws l^3 , acting on the ends of the axle of the roller *l*. The required motion is imparted to these rollers by action of a tappet, *m*, which is secured by a set screw, *m'*, in a standard rising from the shuttle-carriage. As the carriage moves inward, the tappet *m* comes in contact with a pendent lever, *n*, which is suspended loosely from the roller *l'*, and which carries a spring-pawl, *n'*, gearing in the teeth of the ratchet-wheel *n^2*, which is firmly secured to the axle *l^** of the roller *l'*. A suitable weight or spring carries the pendent lever and pawl back to their original position as soon as the tappet *m* recedes. By adjusting the tappet *m* backward or forward the throw of the pendent lever *n* can be decreased or increased, and the consequent increase or decrease in the motion of the take-up rollers produces a corresponding change in the length of the meshes. If the tappet is held stationary until the net is completed, all the meshes will be of uniform size; but, if desired, said tappet may be connected with a device which will change its position automatically after each course or at certain stated intervals, and the nets can be made with gradually-increasing or with gradually-decreasing meshes, as may be desired.

Motion is imparted to the main shaft C by means of a large cog-wheel, C^2 , which gears in a pinion, D' , on the shaft D. This shaft may be rotated by hand or by any other competent power, and the motion of the shaft C is transmitted to the shaft C' by a cog on the circumference of the disk C^{*2} , which gears in the cog-wheel C^2 . If desired, these two cog-wheels may be made oval, to produce a decrease in the velocity of the machine at those moments when the delicate portions of the mechanism are brought into action, and an increase in the velocity at such points where the coarser parts of the mechanism alone have to operate.

Having thus described our invention, we claim as new and desire to secure by Letters Patent—

1. The employment or use, in a loom for making nets, of a series of spools, *a*, carrying the warp-threads, in combination with a stationary comb, *b*, rods *c* *c'*, and rough-surface roller *e*, all constructed and operating substantially as and for the purpose set forth.

2. The rod *d*, in combination with the warp-threads and rough surface roller *e*.

3. The friction-driver e^* and conical roller e^{*2} , in combination with the rough-surface roller *e*, and with the warp-threads applied and operating substantially as and for the purpose set forth.

4. The movable comb *f*, in combination with the twisting-hooks *g*, and with the warp-threads, constructed and operating substantially as and for the purpose set forth.

5. The hooks g , hook-box g' , and rod g^2 , arranged in combination with cam grooves g^4 and cam g^{4*} , in the manner and for the purpose substantially as described.

6. The toothed rack bar g^9 and cam-groove g^{11} , in combination with the hook-box g' , applied and operating substantially as and for the purpose set forth.

7. The straps g^6 and cam-grooves g^8 , in combination with the rods g^3 and hook-box g' , constructed and operating substantially as and for the purpose specified.

8. The lugs g^{12} , with projections and corresponding cavities, acting in combination with the bar g^{13} and hook-box g' , in the manner and for the purpose substantially as described.

9. The flanged circular shoes h^3 , with notches h^4 , in combination with the shuttles, constructed and operating substantially as and for the purpose set forth.

10. The hinged needles h^5 , applied in combination with the shuttles h' , in the manner and for the purpose substantially as specified.

11. The carriage h^7 and rails h^8 , in combination with the shuttles h' and hooks g , constructed and operating substantially as and for the purpose described.

12. The stretcher i , arranged and operated in combination with the shuttles, in the manner and for the purpose substantially as set forth.

13. The combination of the adjustable take-up rollers $l l' l^2$ with the hooks g and shuttles h' , constructed and operating substantially as and for the purpose specified.

14. The adjustable tappet m , acting in combination with the pendent lever n , pawl n' , ratchet-wheel n^2 , and take-up rollers $l l' l^2$, substantially in the manner and for the purpose herein shown and described.
